UNITED STATES PATENT OFFICE.

NANNABELL WHOBREY, OF AKRON, OHIO, ASSIGNOR OF ONE-HALF TO WILLIAM W. GLASGOW, OF AKRON, OHIO.

DESIGN FOR A HAND BAG OR SIMILAR ARTICLE.

Application filed February 21, 1924. Serial No. 8,692. Term of patent 3½ years.

To all whom it may concern:

Be it known that I, NANNABELL WHOBREY, a citizen of the United States, residing at Akron, in the county of Summit and State of Ohio, have invented a new, original, and ornamental Design for a Hand Bag or Similar Article, of which the following is a specification, reference being had to the accompanying drawing, forming part thereof, and in which—

I claim:—

The ornamental design for a hand bag or similar article, as shown.

NANNABELL WHOBREY.
